US00D839267S

(12) **United States Design Patent** (10) **Patent No.:** **US D839,267 S**
(45) **Date of Patent:** **** Jan. 29, 2019**

(54) **DISPLAY DEVICE**

(71) Applicant: **Samsung Display Co., Ltd.**, Yongin-si, Gyeonggi-do (KR)

(72) Inventor: **Sang Hyo Park**, Suwon-si (KR)

(73) Assignee: **Samsung Display Co., Ltd.**, Yongin-si (KR)

(**) Term: **15 Years**

(21) Appl. No.: **29/623,002**

(22) Filed: **Oct. 20, 2017**

(30) **Foreign Application Priority Data**

Apr. 25, 2017 (KR) 30-2017-0019245

(57) **CLAIM**

The ornamental design for a display device, as shown and described.

DESCRIPTION

FIG. 1 is a front perspective view of a display device showing our new invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the display device when folded along a center portion and unfolded along an edge portion; and,

FIG. 9 is a perspective view of the display device when unfolded along the center portion and the edge portion.

The broken lines shown in the drawings depict portions of the display device that form no part of the claimed design.

1 Claim, 9 Drawing Sheets
